UNITED STATES PATENT OFFICE.

MARY A. MALLOY, OF PORTLAND, OREGON, ASSIGNOR, BY MESNE ASSIGNMENTS, TO
GRACE HUDSON.

DOOR FOR FUEL-OPENINGS OF FURNACES.

1,087,885.

Specification of Letters Patent.

Patented Feb. 17, 1914.

Application filed August 20, 1910. Serial No. 573,255.

To all whom it may concern:

Be it known that I, MARY A. MALLOY, a citizen of the United States, and a resident of Portland, county of Multnomah, State of Oregon, have invented a new and useful Improvement in Doors for Fuel-Openings of Furnaces, of which the following is a specification.

My present invention relates to furnaces requiring an air-and-gas-tight combustion chamber, as set forth in my pending application for Letters Patent for an improvement in furnaces, filed July 21, 1910, Serial No. 573,109, and to which reference is hereby had.

The object of this invention is to provide the wall of the casing of said combustion chamber with a fuel opening and a door therefor, which is convenient to make and which when closed provides an efficient air-and-gas-tight closure.

I attain my object in the devices illustrated in the accompanying drawing constituting a part hereof, and in which:

25 Fig. 1 is an exterior view of a portion of the wall of the combustion chamber, provided with an opening through which to introduce fuel, and such fuel-opening being closed by a door embodying my invention; 30 Fig. 2 is a horizontal plan section, approximately taken on a line pointed by the arrow, *x*, in Fig. 1; Fig. 3 is a vertical section approximately taken on a line A—A of Fig. 1.

a represents a portion of the casing of the 35 combustion chamber above the grate. It is provided with an opening, *b*, through which to introduce fuel as required. The rim of such fuel-opening is provided with a ground exterior face, so as to have a substantially 40 air-and-gas-tight fit, with the rim of the door, *c*, which rim is also provided with a ground face. On the interior of wall-section, *a*, are provided hinge lugs, *d*, *d*, between which is hinged an arm, *e*, curved at 45 *f*, and so formed that, when the door is latched, the main portion of said arm will be located in and extend across the full opening, as shown in Fig. 2. Said arm is provided at its free end with an inwardly bent 50 part, *g*, constituting a latch, adapted to be engaged with a lug, *h*, on the interior of the wall, *a*. At the center, *i*, the arm, *e*, is enlarged and provided with a threaded socket, in which rotates the stud-screw, *j*, integrally 55 formed on the interior of the door, *c*, as

more clearly shown in Figs. 2 and 3. The stud-screw, *j*, may be cast hollow to reduce weight of metal, as shown in Fig. 3.

On the exterior of the door *c* is a knob *l*. To open the door the operator grasps the 60 knob *l* and rotates the door, which movement through the medium of the screw removes said door from contact with the casing *a*. Then by slightly elevating the door the outer end of the arm *e*, is raised out of 65 engagement with the lug *h*, whereupon said door may be swung open. In closing the door, the latch-lug *g* on the outer extremity of the arm, *e*, is in the first instance latched with the lug, *h*, and then the door, *c*, is given 70 a half turn to the left, by its knob, so as to seat the rim of the door tightly against the rim of the fuel-opening, *b*.

The abutting faces of the rim of the door, and the fuel-opening, must be adapted to 75 have an air-and-gas-tight contact when the door is closed. This effect is preferably accomplished by providing one of the abutting faces of said parts, as for example the rim of the opening, *b*, with an annular cavity, 80 *w*, V-shaped in cross section, and providing the other part, for example the rim of the door, *c*, with a corresponding annular rib-like protuberance, *y*, so as to cause said abutting faces to interlock with each other when 85 the door is closed.

I claim:

1. The combination with a casing having a door opening a bearing on the inside of the casing adjacent the opening, a bar having 90 one end bent to form a latch in its opposite end extended and re-bent to form a neck provided with an opening a pivot in the latter opening and the bearing to support said bar, the central portion of said bar having a 95 threaded opening, a lug on the inside of the casing to coöperate with the latch on the bar, a door bearing against the outside of the casing adjacent the opening therein a threaded stem extending from the door and 100 engaging the threaded opening in the bar, and a knob on the door whereby upon turning the door it will be removed from the casing and upon lifting the door and bar the latch will be disengaged from the lug and 105 the opening in the casing may be uncovered.

2. The combination of a casing formed with an opening, a bearing on the inside of the casing adjacent the opening, a lug on the inside of the casing a bar pivoted in the 110

bearing, said bar having one end bent to engage the lug, the bar having a threaded opening, a door engaging the outside of the casing and covering the opening in said casing, a threaded stem projecting from the door and engaging the threaded opening in the bar, whereby when the door is turned in one direction the threads will cause the door to move away from the casing and whereby

when said door and bar are raised to disengage the bent end from the lug the door may be swung open to uncover the opening in the casing. 10

MARY A. MALLOY.
